US00D973687S

(12) **United States Design Patent** (10) Patent No.: **US D973,687 S**
Kim et al. (45) Date of Patent: **** Dec. 27, 2022**

(54) **DISPLAY PANEL WITH GRAPHICAL USER INTERFACE**

G06F 3/0486; G06F 3/0487; G06F 3/0488; G06F 3/04883; G06F 3/04886

See application file for complete search history.

(71) Applicant: **ELECTRONICS AND TELECOMMUNICATIONS RESEARCH INSTITUTE**, Daejeon (KR)

(72) Inventors: **Jeong Nyeo Kim**, Daejeon (KR); **Seon-Gyoung Sohn**, Daejeon (KR); **Kyeong Tae Kim**, Daejeon (KR); **Young Ho Kim**, Daejeon (KR); **Yun-Kyung Lee**, Daejeon (KR); **Jae Deok Lim**, Sejong-si (KR)

(73) Assignee: **Electronics and Telecommunications Research Institute**, Daejeon (KR)

(**) Term: **15 Years**

(21) Appl. No.: **29/795,335**

(22) Filed: **Jun. 17, 2021**

(30) **Foreign Application Priority Data**

Feb. 8, 2021 (KR) 30-2021-0006532
